[57] CLAIM

The ornamental design for a kitchen playset with panels for decoration, as shown and described.

DESCRIPTION

FIG. 1 is a perspective view of the kitchen playset with panels for decoration showing our new design;

FIG. 2 is a perspective view of the playset of FIG. 1 with card backing, collapsed to show the fold lines;

FIG. 3 is a front elevation view of the playset of FIG. 1;

FIG. 4 is a rear elevation view of the playset of FIG. 1;

FIG. 5 is a top elevation view of the playset of FIG. 1;

FIG. 6 is a bottom elevation view of the playset of FIG. 1;

FIG. 7 is a right side elevation view of the playset of FIG. 1;

FIG. 8 is a left side elevation view of the playset of FIG. 1 showing oven door open to expose interior features;

FIG. 9 is a partial front elevation view of the playset of FIG. 1 showing oven door open to expose interior features; and,

FIG. 10 is a top elevation view of the playset of FIG. 1 showing oven door open to expose interior features, and sink element extended to expose hidden features.
